EDWIN C. LARRY, OF ROCHESTER, NEW YORK, ASSIGNOR TO GENERAL RAILWAY SIGNAL COMPANY, OF GATES, NEW YORK, A CORPORATION OF NEW YORK.

ADJUSTABLE RESISTANCE.

1,155,826.

Specification of Letters Patent. Patented Oct. 5, 1915.

Application filed June 26, 1915. Serial No. 36,516.

To all whom it may concern:

Be it known that I, EDWIN C. LARRY, a citizen of the United States, and a resident of the city of Rochester, in the county of Monroe and State of New York, have invented a new and useful Adjustable Resistance, of which the following is a specification.

This invention relates to electrical resistance devices more particularly of that class used in railway track circuits, and has for its main object to provide a simple and efficient device of this character having a wide range of adjustment adapting it for use in various situations as a standard resistance device, and with batteries of relatively lower and higher potential, such as potash and storage batteries.

Other objects and advantages will appear as the description of the invention progresses, and the novel features of the invention will be particularly pointed out in the appended claims.

In describing the invention in detail, reference is had to the accompanying drawing, wherein I have illustrated a preferred physical embodiment of my invention, and wherein like characters of reference designate corresponding parts throughout the several views, and in which:

Figure 1 is a partly broken out side elevation of the improved resistance device showing it adjusted for use with low potential or potash batteries; Fig. 2 is a partly broken out side elevation showing the device adjusted for use with storage batteries of higher potential; Fig. 3 is a top plan view showing the parts adjusted as in Fig. 2; Fig. 4 is a bottom plan view of the device; Fig. 5 is an enlarged top perspective view of the adjustable contact; Fig. 6 is a detail vertical transverse section taken on the line *a—a* in Fig. 1, and Fig. 7 is a detail top perspective view of the adjustable contact and its immediate supports.

The numeral 1, indicates the block or body portion of the resistance device, which may be made of porcelain or other insulating material. The block has opposite end lugs 2 receiving screws 3, fastening it to any suitable support 4, in proper relation to any electrically controlled structure to have the current actuating it passed conveniently through the resistance device. The block 1, also has opposite end holes or bores 5, which

are enlarged at the bottom into rectangular recesses 6, in which fit like shaped heads of non-revolvble screw binding posts 7, 8, upon each of which is placed in a longitudinal top recess of the upwardly projected end 60 of the block 1, a rectangular conductive washer 9, having at its inner edge an open eye or channel 10, into which is soldered one terminal of the resistance wire coil. The terminal 11, of the openly coiled bare 65 resistance wire portion 12, is fixed to the washer 9—10, on the post 8, and the terminal 13, of the closely coiled covered fixed or constant resistance wire portion 14, is secured to the washer 9—10, on the post 7. 70 The coil portions 12, 14, are respectively made of coarser and finer wire and their inner adjacent convolutions are conductively connected to permit an electric current to pass from the post 7, to post 8, through 75 the entire resistance coil 14, 12.

Each binding post carries a washer 15, below a nut 16, above which are two other washers 17, 18, outside of which is a fastening nut 19, and a lock nut 20, whereby 80 portions 21, 22, of a line wire may be clamped between the washers 17, 18, of the respective posts, 7, 8, in conductive relation with the washers 9—10, and the resistance coil portions 12, 14. The longer coil portion 12, of coarser bare wire is wrapped around the central reduced substantially rectangular part of the block 1, and is practically buried within grooves 23, formed at its opposite side faces, but the wire bodily overlies the ungrooved upper edge of the block where its successive crossing convolutions are parallel with each other and lie at right angles with opposite faces of the block, as shown in Fig. 3. Fig. 4, of the drawings shows that the convolutions of wire coil portion 12, in passing from one block side groove 23, to its next side groove range 90 through oblique grooves 24, formed in the lower edge of the block thereby permitting the above named true right-angular disposal of the coil convolutions at the upper edge of the block to allow a superposed longitudinally adjustable narrow contact 25, to engage any two adjoining convolutions of coil portion 12, at four points, as hereinafter 95 more fully explained.

The block grooves 23, 24, are all preferably filled over the coil portion 12, with any suitable insulating varnish, which, how- 110

ever, is not applied to the unburied or projecting coil contact portions at the ungrooved upper edge of the block. The longer coarser coil portion 12, and the 5 shorter finer coil portion 14, offer substantially similar resistance to passage of an electric current, which for a track circuit may be about two ohms. As the coil portion 12, has about twenty spaced convolutions passing over the top of the block 1, a shifting of the superposed adjustable contact the distance between any two convolutions will cut out of or into the line a proportionate resistance of one-tenth ohm. 10 thus permitting nicety of resistance adjustment as any special circuit conditions may suggest or require.

The contact 25, is a transversely ranging conductive metal strip whose upwardly 15 pressed central part underlies the cross bar of a U-shaped resilient metal support 26, and may have two central upwardly projecting edge flanges 27, 27, fitting opposite edges of the support. The contact also 20 preferably has two upturned edge flange portions 28, 28, at each curved end part which makes contact with the convolutions of the wire coil 12. Both parts 25, 26, fit loosely upon the reduced end of an adjusting screw 29, which is headed over upon the contact to hold it and the support to the 25 revolvable screw. This screw is threaded into the central bore of a guide 30, which mainly underlies a transverse bar 31, having a slot 32, through which the screw freely 30 passes. At each end the guide 30 has two spaced upturned and indent lugs 33, 33, and the two pairs of lugs inclose opposite edge portions of the bar 31, to maintain true sliding engagement of the guide therewith. The two pairs of lugs 33, also receive between them the resilient upwardly projecting opposite limbs of the U-shaped support 26, whereby the engagement of both support 35 limbs with the pairs of guide lugs 33, prevents turning of the contact 25 and its support 26, upon the screw 29; and thus maintains the contact at true right-angular relation to the resistance block 1, and parallel 40 with the convolutions of the wire coil 12, thereon. The opposite resilient limbs of the support 26, may freely slide vertically between the pairs of lugs 33, at opposite edges of the supporting bar 31. The screw 29, 45 preferably has a milled head 34, and also carries a jam-nut 35, locking against the bar 31, after the contact carrying guide 30, has been properly adjusted on the bar to cut in or out any desired amount of resistance by movement of the contact 25 to proper convolutions of the coil 12. Each of the upturned, concavo-convex ends of contact 25, normally engage or bridge any adjoining two convolutions of the resistance coil 12, with which the contact thus has

four points of engagement, as shown in Figs. 1, 2 and 6, of the drawings, thereby positively maintaining current conductivity between the contact and the coil even if one or two of said points have a more or less 70 uncertain engagement with the coil.

The hole at one end portion of the bar 31 will fit either binding post 7, 8, to which it may be fastened under the washer 15, by the post nuts 16, 19, 20. When the bar is 75 secured at one end to either post the other end of the bar is free thus making the resiliency of the bar available to yieldingly but closely press the contact 25, to the convolutions of the resistance coils 12. During 80 a manual reciprocation of the loosened guide 30, on the bar 31, the resiliency of the bar also assures considerable frictional pressure of the contact 25, upon and across the convolutions of coil 12, to remove from both 85 contact and coil any dust, dirt or oxid accumulations and thus easily maintain the best possible conductivity between the contact and the coil. The upturned contact flanges 28, prevent edgewise catching of the 90 reciprocating contact upon the coil convolutions during this surface cleaning operation. When the bar 31, is fixed to the post 7, as shown in Fig. 1, of the drawings, the current from a weaker potash battery entering by line wire portion 21, will traverse post 8, its washer 9, the terminal 11, of coil 12, and any number of convolutions of said coil which may lie between the terminal 11, and the contact 25 and through said contact 100 and screw 29, and guide 30, to the bar 31, and the post 7, to the other portion 22, of the line wire. During this operation of the resistance device the fixed or constant resistance coil portion 14, is cut out of the 105 line wire circuit which thus meets resistance only through the active convolutions of the coil portion 12, and this resistance may be nicely varied by one-tenth ohm, as desired, by changing the position of the contact 25, 110 upon the bar 31. Should a greater resistance than two ohms be desired, as when storage batteries are used, the bar 31, will be fixed to the post 8, as shown in Fig. 2 of the drawings, and the current now entering 115 at line wire portion 22, will traverse post 7, its washer 9, the terminal 13, of the resistance coil portion 14, and necessarily through the whole of said coil portion, and thence through any one or more of the convolutions of the coil portion 12, which may then lie between said coil portion 14, and the properly adjusted contact 25, and from said contact through the screw 29, and guide 30, to the bar 31, and post 8, to line wire portion 120 21. By thus supporting the contact carrying bar 31, upon the post 8, a minimum resistance of two ohms offered by the coil portion 14, is always available, and to this fixed or constant resistance may be added any further 125 130

ther desired resistance up to the two ohms offered by the entire coil portion 12, or a sum total of four ohms resistance. This added resistance is nicely adjustable by gradations of one-tenth ohm substantially as when the bar 31 is fixed to the other binding post 7. Only such parts of the open coil 12, which pass over the upper edge of the insulating block 1, needs be bare or un-covered, and means other than the screw 29 and nut 35, may be used to bind the adjusted parts 25, 26, 30, to the contact carrying bar 31, as will readily be understood.

Although I have particularly described the construction of one physical embodiment of my invention, and explained the operation and principle thereof; nevertheless, I desire to have it understood that the form selected is merely illustrative, but does not exhaust the possible physical embodiments of the idea of means underlying my invention.

What I claim as new and desire to secure by Letters Patent of the United States, is:

1. An adjustable resistance comprising an insulating block, two binding posts thereon, two connected resistance coils on the block in circuit with the respective binding posts, one coil having open or spaced bare convolutions, a bar adjustable to either post and ranging along the coils, and a contact adjustable on the bar to conductively engage different convolutions of the open coil.

2. An adjustable resistance comprising an insulating block, two binding posts thereon, two connected resistance coils on the block, one coil of bare wire having open or spaced convolutions in circuit with one binding post, and the other close coil of covered wire being arranged at one end of the bare wire coil and in circuit with the other binding post, a bar held to one of the posts and ranging along the coils, and a contact adjustable on the bar to conductively engage different convolutions of the open coil.

3. An adjustable resistance comprising an insulating block, two binding posts thereon, two connected resistance coils on the block, one coil having open or spaced bare convolutions in circuit with one binding post and the other coil having closely wound insulated convolutions in circuit with the other binding post, a bar conductively connected to one of the posts and ranging along the coils, and a contact adjustable on the bar to conductively engage different convolutions of the open coil.

4. An adjustable resistance comprising an insulating block, two binding posts thereon, two connected resistance coils on the block in circuit with the respective binding posts, one coil having open or spaced bare convolutions and the other coil having closely wound insulated convolutions in circuit with the other binding post, a bar conductively

connected to one of the posts and ranging along the coils, and a contact adjustable on the bar and having opposite ends each engaging two convolutions of the open coil and therewith having four points of engagement at any desired adjustment of the contact along the bar.

5. An adjustable resistance comprising an insulating block grooved vertically at its opposite sides and obliquely at its lower edge, two binding posts on the block, two connected resistance coils on the block, one coil of bare wire having open or spaced convolutions in circuit with one binding post and entering said side and lower edge grooves of the block and ranging across its upper edge at right angles to the side walls of the block; and the other coil being arranged at one end of the open coil and in circuit with the other binding post, a bar held to one of the posts and ranging along the coils, and a contact adjustable on the bar to conductively engage different upper convolutions of the open coil.

6. An adjustable resistance comprising an insulating block, two binding posts thereon, two connected resistance coils on the block in circuit with the respective binding posts, one coil having open or spaced bare convolutions, a bar adjustable to either post and ranging along the coils, and a contact adjustable on the bar and having ends each engaging two convolutions of the open coil and therewith having four points of engagement at any desired adjustment of the contact along the bar.

7. An adjustable resistance comprising an insulating block, two binding posts thereon, two connected resistance coils on the block in circuit with the respective binding posts, one coil having open or spaced bare convolutions, a bar held to one of the posts and ranging along the coils, and a contact adjustable on the bar and having opposite end parts engaging the open coil, said contact also having upturned edge flanges at its coil engaging portions permitting unobstructed reciprocation of the loosened contact along the bar and coil for cleaning engaging surfaces of the contact and coil.

8. An adjustable resistance comprising an insulating block, two binding posts thereon, two connected resistance coils on the block in circuit with the respective binding posts, one coil having open or spaced bare convolutions, a bar held to one of the posts and ranging along the coils, and a contact adjustable on the bar and having opposite end parts each engaging two convolutions of the open coil thereby having four points of engagement with said coil at any adjustment of the contact along the bar, said contact also having upturned edge flanges at its coil engaging portions permitting unobstructed reciprocation of the loosened con-

tact along the bar and coil for cleaning engaging surfaces of the contact and coil.

9. An adjustable resistance comprising an insulating block, two binding posts thereon, a bared resistance coil on the block in circuit with the binding posts, a bar held to one of the posts and ranging along the coil, a sliding guide having end flanges engaging opposite edge portions of the bar, a support having ends vertically movable on the end flanges of the guide, a contact below the support, and means holding the contact to the support and also holding the guide to the bar and permitting adjustment of the contact to different convolutions of the coil.

10. An adjustable resistance comprising an insulating block, two binding posts thereon, a bared resistance coil on the block in circuit with the binding posts, a bar held to one of the posts and ranging along the coil, a sliding guide having end flanges engaging opposite edge portions of the bar, a support having ends vertically movable on the end flanges of the guide, a contact below the support, and means holding the contact to the support and also holding the guide to the bar and permitting adjustment of the contact to different convolutions of the coil.

11. An adjustable resistance comprising an insulating block, two binding posts thereon, two connected resistance coils on the block in circuit with the respective binding posts, one coil having open or spaced bare convolutions, a bar held to one of the posts and ranging along the coils, a sliding guide having end flanges engaging opposite edge portions of the bar, a support having ends vertically movable on the end flanges of the guide, a contact below the support, and means holding the contact to the support, and also holding the guide to the bar and permitting adjustment of the contact to different spaced convolutions of the open coil.

12. An adjustable resistance comprising an insulating block, two binding posts thereon, a bared resistance coil on the block in circuit with the binding posts, a bar held to one of the posts and ranging along the coil, a sliding guide having end flanges engaging opposite edge portions of the bar, a support having ends vertically movable on the end flanges of the guide, a contact below the support, and means holding the contact to the support and also holding the guide to the bar and permitting adjustment of the contact to different convolutions of the coil; said contact having central upturned flanges embracing opposite edges of the support.

13. An adjustable resistance comprising an insulating block, two binding posts thereon, a bared resistance coil on the block in circuit with the binding posts, a bar held to one of the posts and ranging along the coil, a sliding guide having end flanges engaging opposite edge portions of the bar, a support having ends vertically movable on the end flanges of the guide, a contact below the support, and means holding the contact to the support and also holding the guide to the bar and permitting adjustment of the contact to different convolutions of the coil; said contact having shaped ends engaging convolutions of the coil and provided with upturned edge flanges permitting unobstructed reciprocation of the loosened contact along the bar and coil for cleaning engaging surfaces of the contact and coil.

14. An adjustable resistance comprising an insulating block, two binding posts thereon, two connected resistance coils on the block in circuit with the respective binding posts, one coil having open or spaced bare convolutions, a bar held to one of the posts and ranging along the coils, a sliding guide having end flanges engaging opposite edge portions of the bar, a support having ends vertically movable on the end flanges of the guide, a contact below the support, and means holding the contact to the support and also holding the guide to the bar and permitting adjustment of the contact to different spaced convolutions of the open coil; said contact having central upturned flanges embracing opposite edges of the support.

15. An adjustable resistance comprising an insulating block, two binding posts thereon, two connected resistance coils on the block in circuit with the respective binding posts, one coil having open or spaced bare convolutions, a bar held to one of the posts and ranging along the coils, a sliding guide having end flanges engaging opposite edge portions of the bar, a support having ends vertically movable on the end flanges of the guide, a contact below the support, and means holding the contact to the support and also holding the guide to the bar and permitting adjustment of the contact to different spaced convolutions of the open coil; said contact having shaped ends engaging convolutions of the open coil and provided with upturned edge flanges permitting unobstructed reciprocation of the loosened contact along the bar and coil for cleaning engaging surfaces of the contact and coil.

EDWIN C. LARRY
